JOHN G. JONES, OF ROCHESTER, NEW YORK, ASSIGNOR TO M. D. KNOWLTON COMPANY,
OF ROCHESTER, NEW YORK, A CORPORATION OF NEW YORK.

SCORING-MACHINE.

1,033,411.

Specification of Letters Patent.

Patented July 23, 1912.

Original application filed July 19, 1906, Serial No. 326,839. Divided and this application filed September 30, 1910, Serial No. 584,635. Renewed June 13, 1912. Serial No. 703,560.

To all whom it may concern:

Be it known that I, JOHN G. JONES, citizen of the United States, and resident of Rochester, in the county of Monroe and State of New York, have invented certain new and useful Improvements in Scoring-Machines, of which the following is a specification.

In paper-board scoring machines the scoring cutters are removably and adjustably mounted on a so-called "cutter-bar" which is rotatively mounted in the frame of the machine whereby it may be turned to a position to permit of the ready and convenient adjustment of the cutters thereon, and thereafter be moved to a position to locate the adjusted cutters in operative relation to an opposing power-driven bed-roll over which the sheets of paper-board are fed to be acted on by said cutters. In some instances the cutter-bars of these scoring machines are provided with two sets of cutters arranged at opposite sides thereof, either of which sets may be brought to operative position relatively to the bed roll by a turning of the bar, which is usually done by hand. To provide for the free and easy turning by hand of said cutter-bar for any of the purposes stated or otherwise, its journals preferably have a slight play or looseness in their bearings, and this play, if not wholly taken up before the scoring operation is commenced, prevents the cutters maintaining with accuracy their adjusted cutting position relatively to the opposing bed-roll during working operation. Because of such fact, it has been the main object of my present invention to provide a simple and readily adjusted means for locking or securing the cutter-bar against undue movement in its bearings upon its adjustment to bring the cutters to operative position. The means for accomplishing such object may be of varied construction, one simple and desirable means being that shown and described in my pending application, Serial No. 326,839, filed July 19, 1906, (of which application this present application is a division), and comprising a compressing means, preferably in the form of a bolt, carrying a plurality of movable sleeves having opposing cam or inclined end faces which coöperate when forced together under the action of the bolt

to move one of said sleeves laterally to locking position; the locking device as a whole being preferably connected with the frame in which the cutter-bar is journaled, and the said laterally movable sleeve thereof being movable to and from a position of locking engagement with the cutter-bar journal, all as hereinafter described in detail and as illustrated in the accompanying drawings, in which—

Figure 1 is a perspective view of the upper part of a paper-board scoring machine embodying my invention, with a part of the frame thereof broken out to show the location of a supported locking device relatively to one of the cutter-bar journals. Fig. 2 is an enlarged end view of the same, also with the frame partly broken out at the locking device, similar to that in Fig. 1. Fig. 3 is an edge view of that part of the machine shown in Fig. 2, looking from the right of the latter, showing the adjusting end of the locking device. Fig. 4 is a side elevation of the two coöperating sleeves of the locking device shown in Figs. 1 and 2. Fig. 5 is a cross-section of one of said sleeves, taken on the line *a—a* in Fig. 4.

Similar reference characters indicate like parts in the several figures of the drawings.

The numeral 1 indicates a hole bored in the end frame post 2 of the scoring machine in a direction transverse to the axis of the journal shaft 3 of the cutter-bar 4. This bore 1 opens into the frame bore 5 forming the journal bearing of the shaft 3, as clearly shown in Fig. 2 of the drawing. From the inner end of the main bore 1 extends a smaller central counter-bore 6 which is internally screw-threaded to receive the inner threaded end of a bolt 7 having a thrust-head 8 carrying a wrench-receiving stud 9. Around the bolt 7 there is placed an inner sleeve 10, the axial bore 11 of which has a larger diameter than that of the bolt to allow lateral play of the sleeve on the bolt. This sleeve 10 has an inclined outer end 12, and also preferably has a convexed inner end 13 bearing against a shoulder 14 at the base of the frame bore 1, and a transverse recess 15 at its under side corresponding to the curvature of the cutter-bar shaft 3. On the bolt 7 between its thrust-head 8 and the sleeve 10 is loosely placed another sleeve 16

in which the bolt is free to turn and which has an inclined end 17 preferably slightly rounded or convexed for engagement with the inclined end 12 of the sleeve 10, with which it co-operates in a manner to be hereinafter described. Fig. 1 of the drawings shows one of these frictional locking devices located in each frame post 2, 2, for co-operation with the opposite end journals of the cutter-bar.

The cutter-bar 4 as shown in the present case has oppositely located dovetail keys 18, 19, to either one or both of which a set of cutters 21 may be attached in usual manner. 15 As here shown but one set of cutters is attached to the cutter-bar, although it is quite usual to attach two sets thereto; the cutter-bar preferably being provided with a suitable hand-grasp 24 as a convenient means 20 to permit the operator to turn the unlocked bar by hand in its journal bearings to bring either of its two sets of cutters into operative relation with the bed-roll 22.

In Fig. 2 of the drawings, the cutter-bar 25 journal bearings 5 are shown somewhat larger than in practice to more clearly illustrate the operation of the invention, which is as follows:—After a set of cutters has been brought into operative relation with 30 the bed-roll 22 and before operation of the machine, the bolts 7 in the end frame posts 2, 2, are turned in or tightened by applying a suitable key wrench to the bolt studs 9. This forces the outer sleeve 16 against the 35 endwise stationary inner sleeve 10, the lateral play of which latter on the bolt allows the co-operating inclined or cam faces 17, 12, of the two sleeves to force the gripping face 15 of the sleeve 10 tightly against the shaft 40 3 of the cutter-bar and clamp the same against movement in its bearings, thereby serving to positively maintain the cutters in adjusted position relatively to the bed-roll and cause them to operate with the desired 45 accuracy in scoring paper-board to the required depth. The inner convexed ends 13 and 17 of the sleeves 10 and 16 respectively, and the enlarged bore 11 of the sleeve 10, permit said sleeve 10 to automatically adjust its gripping face 15 to the shaft 3 under pressure of the bolt 7, as described.

What I claim is:—

1. In a scoring machine, the combination with a frame comprising spaced posts and a 55 cutter-bar journaled in said posts, of a friction locking device carried in each of the posts and engaging against the ends of the cutter-bar, for the purpose set forth.

2. In a scoring machine, the combination 60 with a frame comprising spaced posts and a cutter-bar journaled at its ends in said posts for rotary adjustment, of a friction locking device supported by each of the posts and engaging against the cutter-bar journals, for the purpose set forth.

3. In a scoring machine, the combination with a frame and a cutter-bar journaled in said frame for rotary adjustment, of a friction locking device supported by said frame and engaging against the cutter-bar journal, 70 for the purpose set forth.

4. In a scoring machine, the combination with a frame comprising spaced posts and a cutter-bar journaled at its ends in said posts for rotary adjustment, of a friction locking 75 device supported by each of the posts at a tangent to the cutter-bar journals and engaging against said journals, for the purpose set forth.

5. In a scoring machine, the combination with a frame, and a cutter-bar journaled in said frame for rotary adjustment, of a locking member supported in the frame for engagement with the cutter-bar to hold the same against movement when adjusted, and means supported by the frame for engagement with said locking member to bind the same against the cutter-bar. 80 85

6. In a scoring machine, the combination with a frame and a cutter-bar journaled in said frame for rotary adjustment, of a bolt 90 threaded in said frame, a locking sleeve loosely mounted upon the bolt for lateral movement thereon, and a second sleeve carried upon the bolt having means co-operating with the locking sleeve to bind the latter against the cutter-bar upon the tightening of the bolt.

7. In a scoring machine, the combination with a frame and a cutter-bar journaled in 100 said frame for rotary adjustment, of a bolt threaded into the frame at a tangent to the cutter-bar, a locking sleeve loosely carried upon the bolt for lateral movement thereon and having an inclined end, and a second 105 sleeve carried upon the bolt having an inclined end co-operating with the inclined end of the locking sleeve to bind the latter against the cutter-bar upon the tightening of the bolt. 110

8. In a scoring machine, the combination with the rotary cutter-bar, of a frame in which said bar is journaled having a bore arranged at a tangent to the cutter-bar and also having a counter-bore at the inner end 115 of the main bore, a bolt passing through the main bore and being threaded into the counter-bore, a locking sleeve loosely carried upon the bolt and having an arcuate recess receiving the cutter-bar journal and also having an inclined end, and a second sleeve carried upon the bolt having an inclined end co-operating with the inclined end of the locking sleeve to bind the latter against the cutter-bar upon the tightening of the bolt. 120

9. In a scoring machine, the combination with a frame, a cutter-bar loosely journaled in said frame for rotary adjustment and having a cutter thereon, and an opposing bed-roll co-operative with said cutter, of 130

adjustable means for rigidly locking said cutter-bar against radial movement upon its adjustment to operative position.

10. In a scoring machine, the combination
5 with a frame comprising spaced posts, a cutter-bar journaled at its ends in said posts for rotary adjustment and having a cutter thereon, and an opposing bed-roll coöperative with said cutter, of adjustable means
10 supported by each of said posts for rigidly locking said cutter-bar against vertical movement in its bearings upon its adjustment to operative position.
11. In a scoring machine, the combination
15 with a frame comprising spaced posts, a cutter-bar loosely journaled at its opposite

ends in said posts for rotary adjustment and having a cutter thereon, and an opposing bed-roll coöperative with said cutter, of a friction locking device carried in each of 20 the posts and engaging the cutter-bar journals to rigidly lock the cutter-bar against vertical and rotary movement upon its adjustment to operative position.

Signed at Rochester, in the county of 25 Monroe and State of New York, this 24th day of September, 1910.

JOHN G. JONES.
